(57) **CLAIM**

The ornamental design for a folding knife, as shown and described.

DESCRIPTION

FIG. 1 is a perspective view of a folding knife according to the present invention, wherein the blade is extended; FIG. 2 is a left side view of the folding knife of FIG. 1; FIG. 3 is a right side view of the folding knife of FIG. 1; FIG. 4 is a top view of the folding knife of FIG. 1; FIG. 5 is a bottom view of the folding knife of FIG. 1; FIG. 6 is a front view of the folding knife of FIG. 1; FIG. 7 is a back view of the folding knife of FIG. 1; and, FIG. 8 is a perspective view of the folding knife of FIG. 1 with the blade folded.

The broken lines depict portions of the folding knife in which the design is embodied that are not considered part of the claimed design.
